UNITED STATES PATENT OFFICE.

RALPH J. GAUDY, OF DETROIT, MICHIGAN.

METHOD OF PRODUCING SMOKE FOR CURING MEATS.

1,225,798.

Specification of Letters Patent. Patented May 15, 1917.

Application filed November 16, 1916. Serial No. 131,669.

To all whom it may concern:

Be it known that I, RALPH J. GAUDY, a citizen of the United States of America, residing at Detroit, in the county of Wayne 5 and State of Michigan, have invented certain new and useful Improvements in Methods of Producing Smoke for Curing Meats, of which the following is a specification, reference being had therein to the accompanying drawings.

The invention relates to a method for producing smoke, being particularly adapted for use in the curing of meats, and it is the object of the invention to obtain a continuous and uniform production of smoke without ignition of the smoke-producing material.

In the present state of the art smoke is usually produced by imperfect combustion 20 of the smoke-producing material. It is difficult to control combustion so as to maintain uniform smoke production and the apparatus employed requires attention. With my improved method and apparatus the operation 25 may be entirely automatic and without danger of igniting the smoke-producing material or variation in quantity of smoke produced. This is accomplished by the use of an electrical heating unit proportioned 30 to limit the temperature below the ignition point, and by means for feeding the unit through the material for producing the smoke.

In the drawings:

Figure 1 is a perspective view illustrating 35 an electrical heating unit suitable for use with my improved method;

Fig. 2 is an elevation showing the unit in use, for producing smoke. 40 A is a suitable container for the smoke and material to be treated thereby. B is a pile of the smoke-producing material, such as sawdust, arranged in the base of the container, and C is an electrical heating unit, 45 preferably initially placed upon the top of the pile and fed by gravity through the same during the operation. The unit may be of any suitable construction, but as specifically shown in Fig. 1, it comprises a 50 frame D having depending studs E thereon, with a resistor wire or ribbon F laced back and forth over said studs and suitably insulated. The resistor may be either exposed or armored, and the current may be supplied 55 through a flexible conductor G.

With the construction as described in operation, when current is passed through the resistor the heat developed is sufficient to carbonize the material B and to produce the smoke, but the proportion is such as to 60 limit the temperature below the ignition point. Consequently the material will not be ignited, but as it is carbonized the weight of the frame F will cause downward feed, this continuing until the entire pile is consumed. 65

While I have described an apparatus having a gravity feed, it is obvious that any means of feeding the heater through the material will be equally operative. 70

What I claim as my invention is:—

1. The method of producing smoke, comprising the electrical generation of heat limited in temperature to less than required for ignition of the smoke-producing material, and the subjection of said material to 75 said heat generation.

2. The method of producing smoke, comprising the electrical generation of heat, limiting the temperature to less than the 80 ignition point of the smoke-producing material, and relatively feeding the material and electrical heat generator to produce a continuous and uniform smoke production.

3. The method of producing smoke, comprising the passing of an electrical current through a resistor proportioned to generate in said resistor heat limited in temperature to less than the ignition point of the smoke-producing material, and feeding said resistor through the smoke-producing material. 85

4. The method of producing smoke, comprising the passing of an electric current through a resistor, placing said resistor on 90 the top of a pile of smoke-producing material, and feeding the same by gravity through said pile.

5. The method of producing smoke, comprising the generation of heat in a heater, 100 of a temperature less than the ignition point of the smoke-producing material but sufficiently high to carbonize said material, placing said heater on the top of a pile of smoke-producing material and feeding the same by 105 gravity through said pile.

In testimony whereof I affix my signature.

RALPH J. GAUDY.
